CLAIM

The ornamental design for a bricklaying trowel, as shown.

DESCRIPTION

FIG. 1 shows a top perspective view of a bricklaying trowel showing my new design according to a first embodiment;

FIG. 2 shows a top view thereof;

FIG. 3 shows a bottom view thereof;

FIG. 4 shows a left side view thereof;

FIG. 5 shows a right side view thereof;

FIG. 6 shows an enlarged and inverted front end view thereof;

FIG. 7 shows an enlarged rear end view thereof;

FIG. 8 shows a top perspective view of a bricklaying trowel showing my new design according to a second embodiment;

FIG. 9 shows a top view thereof;

FIG. 10 shows a bottom view thereof;

FIG. 11 shows a left side view thereof;

FIG. 12 shows a right side view thereof;

FIG. 13 shows an enlarged and inverted front end view thereof; and,

FIG. 14 shows an enlarged rear end view thereof.

The broken lines depict portions of the bricklaying trowel in which the design is embodied that form no part of the claimed design.
